Primary Examiner—Alan P. Douglas*Assistant Examiner*—Jeffry H. Musgrave*Attorney, Agent, or Firm*—Beaman & Beaman[57] **CLAIM**

The ornamental design of a collet and tool holder tray, substantially as shown and described.

DESCRIPTION

FIG. 1 is a top plan view of a collet and tool holder tray in accord with my new design of a configuration for mounting upon a machine tool column;

FIG. 2 is a bottom view of the tray of FIG. 1;

FIG. 3 is a front elevational view of my new design as taken from the bottom of FIG. 1;

FIG. 4 is a rear elevational view as taken from the top of FIG. 1;

FIG. 5 is a side elevational view as taken from the right of FIG. 1;

FIG. 6 is a side elevational view of my new design as taken from the left of FIG. 1;

FIG. 7 is a top plan view of another embodiment of my collet and tool holder tray design for mounting upon a flat surface;

FIG. 8 is a bottom view of the tray design of FIG. 7;

FIG. 9 is a front elevational view as taken from the bottom of FIG. 7;

FIG. 10 is a rear elevational view as taken from the top of FIG. 7;

FIG. 11 is a side elevational view as taken from the right of FIG. 7; and,

FIG. 12 is a side elevational view of my new design as taken from the left of FIG. 7.
